UNITED STATES PATENT OFFICE.

LARS H. VOLD, OF BUTLER, PENNSYLVANIA.

ADJUSTABLE DRILL CHUCK.

Application filed February 4, 1925. Serial No. 6,692.

This invention relates to multiple drill presses, and particularly to adjustable drill chucks for use in connection therewith.

Heretofore, in drill presses of this character, it has been frequently not only inconvenient to easily, quickly, and accurately adjust the entire number or gang of bits used to the desired relative positions axially of the bits but great difficulty has been experienced to 10 positively lock the bits against displacement after the desired adjustment is made. It is highly desirable to provide a multiple drill press equipped with means which will enable the operator to easily and quickly bring the 15 tips of all of the bits employed into exact alignment, or other necessary relative disposition required by the work being operated upon, which will at the same time assure such setting being positively maintained when once made, regardless of the simultaneous bodily movement of the entire gang of bits as a unit during repeated use. It is the object of the invention to provide 20 a construction possessing the advantages 25 noted.

It is a special object to provide a construction in which the rotating driving spindle for each of the bits includes a tool-holding element connected thereto adapted to contact an adjustable abutment carried by the spindle threadedly mounted axially of the spindle and provided at one end with a contact face with the side face of the threads 30 contacting the abutment facing towards the end contact face especially inclined and diverging away from the same whereby to increase its area of contact with the abutment, and preferably of greater area than the opposite side face of the thread.

It is also a special object to provide a construction in which the means rotatably driving the drill bits includes a rotatable spindle, a tool-carrying element and a limiting abutment both threadedly mounted upon a 40 suitable part carried by the spindle, the side face of the thread contacting the abutment and facing towards the end thereof provided with the limiting contact face being especially inclined whereby the said side face 45 diverges radially from the axis of the spindle at a smaller angle than the opposite side face of said thread.

It is another special object to provide a construction in which the threaded connection 50 between the adjustable abutment and driving spindle is such as to generate under

the axial thrust of the tool-carrying element a greater frictional resistance between the said abutment and the driving spindle to turning movement upon the spindle than 60 that exerted between the contacting portions of the tool-carrying element and the said abutment.

It is still a further special object to provide a drill chuck having a tool-holding element 65 and an adjustable limiting abutment both threadedly mounted upon a driving spindle so constructed or provided with means for reducing the friction between the contacting surfaces of the said element and abutment 70 whereby the tendency of the turning movement of the tool-holding element to effect turning movement of the abutment will be reduced to a minimum.

These and other objects of the invention 75 will more fully appear when taken in conjunction with the following description and the appended claims.

In the accompanying drawings forming a part of the application, Fig. 1 is a fragmentary perspective view of a portion of a multiple drill press equipped with the present invention; Fig. 2 a side elevation of one form of the invention, illustrating the rotatable driving spindle and the remaining portions forming the adjustable drill chuck on an enlarged scale; and Fig. 3 a similar view, 80 shown partly in section and partly in elevation, illustrating a modified form of the invention.

In the drawings, 1 represents the frame of a multiple drill provided with the head 2, and the work table 3, all as common to machines of this same general character. The machine may be equipped with any desired 85 number of chucks, each of which is rotatable and driven by means of a separate driving spindle through suitable gearing housed within the head 2 and the super-structure of the press. None of these parts, except in 90 so far as subsequently described form a part of the present invention, and have therefore not been illustrated in greater detail, the showing in Fig. 1 being sufficient to those familiar with this art to clearly indicate the 95 method of mounting the chucks and their coordination with the remaining parts.

In both forms of the invention illustrated, a rotatable driving spindle 4 is provided for each of the bits 5, the usual tapered shank 5' 100 of the bits being adapted to be received by a correspondingly shaped socket at one end

of a tool-holding or carrying element designated generally by the reference numeral 6, all as common in the art.

The element 6 is cylindrical in shape and provided with an axial internally threaded bore extending inwards from its end opposite the bit-receiving socket which bore threadedly receives the terminal exteriorly threaded portion 4' of the driving spindle 4. Also threadedly mounted upon the terminal of the driving spindle and in axial alignment with the tool-holding element 6 is a cylindrical abutment collar 7.

The portion of the terminal 4' which operates with the abutment collar 7, the interior threads on the collar of course being correspondingly formed, is equipped with peculiarly shaped threads in which the side face 8 thereof facing the end contact face on the tool-holding element is especially inclined away from the said contact face, and diverges radially from the axis of the spindle in the direction of the head 2, thereby increasing the area of the said side face over that of the opposite side face of the thread. In other words, the side face 8 is so shaped as to diverge radially from the axis of the spindle at a smaller angle than the opposite side face of the thread, both faces of course following the customary pitch of the thread as a whole.

Although this feature need not be extended to the portions of the threaded terminal 4' coating only with the tool-holding element, for convenience in manufacture and manipulation the same form of thread is used throughout the entire terminal portion of the spindle cooperating with both the tool-holding element 6 and the abutment collar 7.

To this point of the description both embodiments of the invention, as illustrated in the drawings, are identically alike and the corresponding parts thereof have been designated by the same reference numerals.

In the form shown in Fig. 2, the end face 9 of the tool-holding element is adapted to directly abut in intimate contact the contiguous end contact face 10 of the abutment, and for a purpose to be subsequently described more at length these end faces are highly polished to produce plane smooth surfaces thereby reducing friction therebetween and the tendency of the one to turn in response to turning movement of the other. To facilitate the manual adjustment, both these members may be knurled over appropriate areas as indicated at 11 and 12.

The modification shown in Fig. 3 differs from that of Fig. 2 in that an anti-friction bearing is interposed between the contiguous end faces of the tool-holding element 6 and the abutment collar 7. As illustrated, a ball bearing is employed comprising the ball retaining ring 13 having suitably spaced

apertures for receiving the anti-friction balls 14 which are adapted to contact and ride upon the end faces of the element 6 and the abutment 7, the diameter of the balls being preferably slightly greater than the thickness of their retaining ring, as clearly shown in the drawings. The interposition of this special anti-friction bearing eliminates substantially all friction between the element 6 and the abutment 7 thereby practically obviating all tendency for the collar to turn upon the spindle due to rotation of the tool-holding element. Due to this fact, it has been found with this form of the invention the specially inclined face 8 on the thread may be dispensed with and ordinary forms of threads employed instead.

The method of adjusting the gang of bits, preliminarily to the actual drilling operation, will now be described. The several tool-holding elements 6 are rotated causing them to ride upon their spindles so as to bring the tips of all of the bits 5 into exact alignment in which all of the tips will lie in the same plane or into any relative positions axially of the spindle, as required by the character of the work being operated upon. When thus positioned the abutment collars 7 are rotated causing them to ride towards the tool-holding elements until brought into contact therewith, as shown in Fig. 2, or into contact with the anti-friction bearings as shown in Fig. 3.

Alternatively, the collars 7 may first be brought to the necessary positions upon the spindles and the tool-holding elements then rotated to cause them to ride towards the abutment collars until a similar contact is established. The latter method is facilitated by driving the spindles, as in the normal operation of the press, and permitting the tips of the bits to come into contact with the surface of the material to be drilled, in which event the elements 6 will ride upwardly on the spindles until the above described contact is made either directly with the collars 8 or until the anti-friction bearings strike the collars.

With either method, as soon as intimate contact is made between the parts, movement of the tool-holding elements axially of the spindle is immediately and positively arrested whereby to absolutely prevent further riding of the said elements upon the spindles, and assuring the tips of the bits being held in the relative positions desired and determined by the adjustments previously made.

With constructions such as illustrated, there is substantially no tendency for the abutment collars to turn about the spindles under the influence of the power transmitted to the bits and their holding elements, which explains the positive setting effect and

the permanence thereof after the necessary adjustments have been accomplished.

Contact of the bit with the work tends to bodily rotate the element 6 upon the spindle in the customary manner well known to those familiar with this art, but due to the smoothly polished plane surfaces provided on the end contact faces 9 and 10, in Fig. 2, the frictional resistance between them is sufficiently reduced to substantially eliminate all tendency of the abutment collar 8 to turn with the element 6 upon the spindle until a sufficiently powerful axial thrust is exerted against the collar to lock the collar, for the results desired, positively to the spindle. The binding effect between the abutment collar and the portion of the spindle upon which it is mounted is greatly enhanced by the provision of the inclined 20 side face 8 of the thread which not only increases the area of contact between the collar and the spindle but serves to generate an effective radial component resulting from the axial thrust of the tool-holding element 25 upon the collar which aids in bringing the interior surface of the collar into a most intimate gripping relation with respect to the exterior surface of the spindle.

In the form shown in Fig. 3, the frictional contact between the element 6 and the collar 7 is practically totally eliminated due to the interposition of the anti-friction bearing therebetween. Consequently, substantially no turning moment whatever is transferred by the tool-holding element to the abutment collar, giving full effect to the axial thrust against the collar in producing the gripping action of the collar upon the spindle.

It is thus seen that the invention provides a drill chuck which is simple in construction, easy to manipulate, freely accessible, readily adjustable, and which will positively lock the tool-holding elements against displacement upon their spindles after the necessary preliminary adjustments have been made.

As required by the patent statutes, the preferred embodiment of the invention has been illustrated and described. It is obvious, however, that various changes in the details and in the arrangement of the several parts can be made without departing from the spirit of the invention. For instance, the shapes of the driving spindle and the tool-holding element may be reversed, that is, the terminal of the driving spindle may be in the form of an internally threaded tube while the upper portion of the tool-holding element is in the form of a solid rod exteriorly threaded to cooperate with the internal threads of the spindle, in which event the abutment collar will threadedly

ride upon the threaded portion of the tool-holding element, its upper end face serving as its contact face which abuts the end face 65 of the spindle. The specially inclined face of the thread in this case, as in the previously described forms, face towards the end contact face of the abutment. It is therefore not intended to limit the invention beyond that particularly pointed out and defined by the appended claims.

I claim:

1. In a multiple drill press the combination with a plurality of driving spindles, of tool-holding elements threadedly connected to the spindles, a limiting abutment adjustable axially of the spindles threadedly mounted in axial alignment with the tool-holding elements and provided at one end 75 with a contact face, the side face of the thread engaging the said abutment and facing towards the said contact face being inclined and diverging away from the said contact face.

2. In a multiple drill press the combination with a plurality of driving spindles, of tool-holding elements threadedly connected to the spindles, a limiting abutment adjustable axially of the spindles threadedly mounted in axial alignment with the tool-holding elements and provided at one end 90 with a contact face, the side face of the thread engaging said abutment and facing towards the said contact face being inclined 95 away from the contact face and having an area greater than the opposite side face of the threads.

3. In a multiple drill press the combination with a plurality of driving spindles, of 100 tool-holding elements threadedly connected to the spindles, a limiting abutment adjustable axially of the spindles threadedly mounted in axial alignment with the tool-holding elements, the side face of the thread 105 engaging the said abutment and facing toward the said contact face being inclined away from the contact face and diverging radially from the axis of the spindle at a smaller angle than the opposite side face 110 thereof.

4. In a multiple drill press the combination with a plurality of driving spindles, of tool-holding elements threadedly connected to the spindles, a limiting abutment adjustable axially of the spindles threadedly mounted in axial alignment with the tool-holding elements, the contact-portions of the 115 said element and abutment being smoothly polished to form plane surfaces whereby to reduce the tendency of the one to turn in response to turning movement of the other.

In testimony whereof, I sign my name.
LARS H. VOLD.
